(57) **CLAIM**

The ornamental design for a suction cup noise making toy, as shown and described.

DESCRIPTION

FIG. 1 is a front perspective view of the first embodiment of the suction cup noise making toy;

FIG. 2 is a rear perspective view of the suction cup noise making toy;

FIG. 3 is a front elevation view of the first embodiment of the suction cup noise making toy;

FIG. 4 is a first side elevation view of the first embodiment of the suction cup noise making toy;

FIG. 5 is a second side elevation view of the first embodiment of the suction cup noise making toy;

FIG. 6 is a rear elevation view of the first embodiment of the suction cup noise making toy;

FIG. 7 is a top plan view of the first embodiment of the suction cup noise making toy;

FIG. 8 is a bottom plan view of the first embodiment of the suction cup noise making toy;

FIG. 9 is a front perspective view of the first embodiment of the suction cup noise making toy;

FIG. 10 is a rear perspective view of the suction cup noise making toy;

FIG. 11 is a front elevation view of the first embodiment of the suction cup noise making toy;

FIG. 12 is a first side elevation view of the first embodiment of the suction cup noise making toy;

FIG. 13 is a second side elevation view of the first embodiment of the suction cup noise making toy;

FIG. 14 is a rear elevation view of the first embodiment of the suction cup noise making toy;

FIG. 15 is a top plan view of the first embodiment of the suction cup noise making toy;

FIG. 16 is a bottom plan view of the first embodiment of the suction cup noise making toy;

FIG. 17 is a front perspective view of the second embodiment of the suction cup noise making toy;

(Continued)

FIG. 18 is a rear perspective view of the suction cup noise making toy;
 FIG. 19 is a front elevation view of the second embodiment of the suction cup noise making toy;
 FIG. 20 is a first side elevation view of the second embodiment of the suction cup noise making toy;
 FIG. 21 is a second side elevation view of the second embodiment of the suction cup noise making toy;
 FIG. 22 is a rear elevation view of the second embodiment of the suction cup noise making toy;
 FIG. 23 is a top plan view of the second embodiment of the suction cup noise making toy;
 FIG. 24 is a bottom plan view of the second embodiment of the suction cup noise making toy;
 FIG. 25 is a front perspective view of the second embodiment of the suction cup noise making toy;
 FIG. 26 is a rear perspective view of the suction cup noise making toy;
 FIG. 27 is a front elevation view of the second embodiment of the suction cup noise making toy;
 FIG. 28 is a first side elevation view of the second embodiment of the suction cup noise making toy;
 FIG. 29 is a second side elevation view of the second embodiment of the suction cup noise making toy;
 FIG. 30 is a rear elevation view of the second embodiment of the suction cup noise making toy;
 FIG. 31 is a top plan view of the second embodiment of the suction cup noise making toy; and,
 FIG. 32 is a bottom plan view of the second embodiment of the suction cup noise making toy.
 The evenly spaced broken lines in the drawing figures show portions of the suction cup noise making toy that form no part of the claimed design.

1 Claim, 12 Drawing Sheets
